UNITED STATES PATENT OFFICE.

JAMES BURN, OF CHESTER, PENNSYLVANIA.

HEADLIGHT-SHIELD.

1,210,272.

Specification of Letters Patent. Patented Dec. 26, 1916.

Application filed June 9, 1916. Serial No. 102,748.

To all whom it may concern:

Be it known that I, JAMES BURN, a citizen of the United States, residing at Chester, in the county of Delaware and State of Pennsylvania, have invented new and useful Improvements in Headlight-Shields, of which the following is a specification.

This invention relates to motor vehicle headlights, and has particular reference to 10 automobile lamps.

It is the primary object of the invention to provide a shield for lamps of the above mentioned character with a view of lessening the glare and brilliancy of the lamp, which 15 impairs the vision of pedestrians and others, and yet properly illuminate the ground or surface in advance of the machine.

In carrying out the invention I provide a shield for the above mentioned purpose, 20 which is in the nature of an attachment for the lamp, and capable of being easily and quickly associated therewith, or removed therefrom when it is desired to increase the brilliancy of the lamps on country roads or 25 the like.

The nature and advantages of the invention will be better understood when the following description is read in connection with the accompanying drawing, the invention re- 30 siding in the construction, combination and arrangement of parts as claimed.

In the drawing forming part of this specification like numerals of reference indicate similar parts in the several views and where- 35 in:—

Figure 1 is a front elevation of a lamp showing the shield associated therewith. Fig. 2 is a side elevation. Fig. 3 is a detail section on line 3—3 of Fig. 2. Fig. 4 is a 40 view of the shield removed.

Referring more particularly to the drawing in detail A indicates generally a lamp of any suitable character, and B the shield forming the subject matter of my invention.

45 The shield as shown in this particular in-

stance embodies a relatively narrow semi-cylindrical frame indicated at 10 and with which the marginal edge of an opaque or semitransparent element 11 is riveted or otherwise secured as at 12. The material 11 50 is preferably semitransparent, consisting of a piece of celluloid which can vary in color, and of a size to cover substantially half of the glass 13 of the lamp when the shield is associated with the latter. Projecting 55 rearwardly from the frame 10 adjacent each extremity is an apertured lug 14 which rests upon the edge of the lamp, having the aperture therein registering with a tapered opening 15 in the body of the lamp for the re- 60 ception of a suitable fastening element such as a thumb screw 16.

Manifestly the shield is in the nature of an attachment which can be quickly and easily associated with the lamp when its use 65 is desired, and just as quickly and easily removed therefrom by loosening the thumb screw 16 as is desirable when traveling over country roads.

While I have shown and described what 70 I consider the preferred embodiment of the invention I desire to have it understood that I do not limit myself to this precise construction, and that such changes may be resorted to when desired as fall within the scope of 75 what is claimed.

What is claimed is:—

A motor vehicle headlight shield comprising a relatively narrow semicylindrical frame adapted to bear against the front of 80 the lamp, a light obscuring element having its marginal edge secured to the frame and shaped to cover approximately one-half of the glass, offset portions forming part of said frame of the lamp, and set screws 85 passed through said offsets for threaded engagement with the lamp to hold the shield fixed thereon.

In testimony whereof I affix my signature.
JAMES BURN.
